UNITED STATES PATENT OFFICE.

ROY W. IDE, OF SPRINGFIELD, ILLINOIS.

INTERNAL-COMBUSTION ENGINE.

1,163,542.

Specification of Letters Patent.

Patented Dec. 7, 1915.

Application filed May 17, 1915. Serial No. 28,695.

To all whom it may concern:

Be it known that I, Roy W. Ide, citizen of the United States, residing at Springfield, in the county of Sangamon and State of Illinois, have invented a certain new and useful improvement in Internal-Combustion Engines, of which the following is a full, clear, concise, and exact description, reference being had to the accompanying drawings, forming a part of this specification.

My invention relates to internal combustion engines of the class employing moving valving cylinders and has for one of its objects the provision of an improved lubricating arrangement whereby lubricant may be supplied to the valving cylinders without finding material access through the ports thereof even though the lubricant be supplied under pressure, as is preferred. In accordance with another feature of the invention such pressure is substantially constant.

The invention has for another of its objects the provision of means whereby the valving cylinders may be moved longitudinally of their axes to bring them toward and from seats which are provided at the intake ends of the engines in a manner to move the valving cylinders from said seats during the intake and exhaust periods and to maintain them nearer said seats during compression and expansion, an arrangement which permits the accumulation of carbon between said seats and the cylinders which will effectively operate as packing during compression and expansion and affords opportunity to add more carbon to the packing to compensate for wear, and whereby the friction load in engines of small horse power is reduced.

As I have practised my invention the valving cylinders are preferably rotated and may also serve as the main operating cylinders of the engines in which the pistons reciprocate, though the invention is not to be limited to these characteristics.

I will explain my invention more fully by reference to the accompanying drawings showing the preferred embodiment thereof and in which—

Figure 1 is a vertical elevation of a single cylinder engine equipped in accordance with the objects of my invention; Fig. 2 is a sectional view on line 2 2 of Fig. 1; Fig. 3 is a sectional view on line 3 3 of Fig. 1; Fig. 4 is a diagram illustrating the extent of

turning movement of the valving cylinder during the intake, compression, expansion, and exhaust periods; Fig. 5 is a diagram illustrating the extent of turning movement of the engine shaft during the intake, compression, firing and expansion, and exhaust periods; Fig. 6 is a view on line 6 6 of Fig. 1; Fig. 7 shows a detail of construction; Fig. 8 is a sectional view on line 8 8 of Fig. 1; Fig. 9 is a detail of a part of the structure as it appears in Fig. 1; Fig. 10 is a view of a lubricant oil circulating pump which may be employed; and Fig. 11 is a diagram illustrating the cam action occurring during the intake, compression, expansion, and exhaust periods for the purpose of adjusting the valving cylinder toward and from the seat.

Like parts are indicated by similar characters of reference throughout the different figures.

The engine shaft 1 carries a fly wheel 2 and is provided with cranks 3 for turning it, these cranks being connected with the inner end of a pitman 4 whose outer end is swingingly connected with a piston 5, all in accordance with well known practice. The upper portion 6 of the engine casing is desirably made cylindrical and is co-axial with an inner cylinder 7, spacing 8 intervening between the inner cylinder 7 and the outer cylinder 6 for the reception of engine cooling fluid that may be circulated through said spacing, as will be understood by those skilled in the art. A cap 9 has portions that constitute end walls for the cylinders 6 and 7, there being a sparking plug 10, desirably co-axially arranged with respect to the cylinders and projecting through the cap 9 to present its electrodes 11 and 12 to the spacing between the upper end of the piston 5 and the end wall 9. The working cylinder 13 of the engine receives the piston 5 and is desirably also caused to function as a valving cylinder, to which end it is provided with two ports 14 and 15, each adapted to serve, first, as an intake port and, secondly, as an exhaust port, the valving cylinder being desirably arranged to operate in a counter-clockwise direction as it is viewed from above. Each of the ports 14 and 15, is, in its turn, brought into alignment with the admission port 16 and the exhaust port 17, and inasmuch as there are two ports 14 and 15, the valving cylinder is caused to turn a half revolution (during which one

or the other of the ports 14 and 15 operates through a complete cycle that embraces the intake, compression, expansion, and exhaust periods) during two revolutions of the engine shaft. The gearing by which the valving cylinder is thus driven at quarter engine speed includes the worm wheel 18 co-axial with and driven by the engine shaft 1, the worm shaft 19 upon the vertical shaft 20 and meshing with the worm wheel 18, the pinion 21 upon the upper end of the shaft 20, and the circular rack 22 carried upon the lower end of the cylinder 13 and meshing with the pinion 21. From the foregoing it will be observed that the valving cylinder completes two cycles in each revolution, the port 14 functioning in one of these cycles and the port 15 functioning in the other of these cycles, as will be apparent from the diagram of Fig. 4 and as will be understood by those skilled in the art.

The spiral diagram of Fig. 5 is spaced off to show the extent of turning movement of the engine shaft during the intake, compression, firing and expansion, and exhaust periods, a comparison of the diagrams of Figs. 4 and 5 illustrating the relative extent of movement of the valving cylinder and engine shaft during each of these periods, all as will be readily understood by those skilled in the art. The upper end face of the cylinder 13 lies in a single plane that is perpendicular to the axis of the cylinder and the opposing surface of the cap 9 also is in a single plane. The lower end of the cylinder carries a cam formation 23 that operates upon a cam seat 24. The cams 23 and 24 co-operate to cause the cylinder 13 to drop a slight distance from the cap 9 during the intake and exhaust periods (see Fig. 11) and to be nearest this cap during the compression and expansion periods, sufficient distance occurring between the inner face of the cap 9 and the upper end of the cylinder 13 to permit of the reception of sufficient carbon to afford a packing 13^a at the upper end of the cylinder there to prevent the escape of gas. When the cylinder 13 is lowered, the spacing between the cylinder and cap 9 is increased to permit of the reception of additional carbon to replace that which may have been worn away, any carbon in excess of that required being removed by the grinding action that occurs when the cylinder is operating during the compression and expansion periods. By this arrangement the wear upon the packing at the upper end of the cylinder is compensated for to reduce gas leakage, and the friction load in engines of small horse power is materially reduced due to the dropping of the cylinder and the consequent reduction of wear upon the packing. Annular spacing 25 occurs between the cylinders 7 and 13, this spacing being located between the bottom of the cylinder 13

and the ports 14, 15, 16 and 17, the cylinders 7 and 13 being in working fit above and below said spacing. Lubricating oil is desirably admitted to the spacing 25 through a pipe 26 which has communication with the bore 27 that is provided in the shaft 20. Oil is desirably forced through the pipe 26 at suitable and preferably constant pressure, say thirty pounds, the oil being desirably forced upwardly through the bore 27 by means of the pump such as illustrated in Fig. 10. The supply of oil is desirably contained in the bottom of the engine case and is forced upwardly through the bore by means of the meshing pinions 28. A valve 29 will relieve the pressure upon the oil directed upwardly through the bore 27 if the pump pressure should exceed predetermined pressure. The oil finding access to the annular spacing 25, will work its way toward both ends of the cylinder 13, a portion of the oil entering the spacing in which the gears 21 and 22 operate to lubricate these gears while another portion will work its way to the annular spacing 30 from which it will find downward passage through the piping 31 to lubricate the main engine shaft. The spacing 30 also operates as a trap to prevent the oil from being forced into the plane of the ports 14, 15, 16 and 17 so that the forcibly fed lubricant will not find access, to any material extent, into the working space provided for the piston, the piston being lubricated in other ways familiar to those skilled in the art. As the part of the cylinder 13 below the ports carries the load no special provision need be made for lubricating the upper part of the cylinder and clearance may intervene between this upper part and the surrounding cylinder.

While I have herein shown and particularly described the preferred embodiment of my invention I do not wish to be limited to the precise details of construction shown as changes may readily be made within the scope of the appended claims without departing from the spirit of my invention, but having thus described my invention I claim as new and desire to secure by Letters Patent the following:

1. An internal combustion engine including an engine rotated valving cylinder, a seat at the intake end of the engine, a packing interposed between the seat and the adjacent end of the valving cylinder, and means for decreasing the spacing between said seat and cylinder during the compression and expansion periods to enable the packing to function and permitting an increase of such spacing non-coincidentally with said periods.

2. An internal combustion engine including an engine rotated valving cylinder which also constitutes the working cylinder of the engine, a piston operating within the

cylinder, a seat at the intake end of the engine, a packing interposed between the seat and the adjacent end of the valving cylinder, and means for decreasing the spacing between said seat and cylinder during the compression and expansion periods to enable the packing to function and permitting an increase of such spacing non-coincidentally with said periods.

10 3. An internal combustion engine including an engine rotated working cylinder, a piston operating within the working cylinder, a seat at the intake end of the engine, a packing interposed between the seat and the adjacent end of the working cylinder, and means for decreasing the spacing between said seat and cylinder during the compression and expansion periods to enable the packing to function and permitting 15 an increase of such spacing non-coincidentally with said periods.

4. An internal combustion engine including an engine rotated valving cylinder having a port, a second cylinder co-axial with the first and in engagement therewith, and means for feeding lubricant to engaged portions of the cylinders between said port and the engine shaft, portions of the cylinders thus lubricated being relatively formed for 20 diverting the flow of lubricant from the port.

5. An internal combustion engine including an engine rotated valving cylinder which also constitutes the working cylinder 25 of the engine, a piston operating within said cylinder for turning the engine shaft, a second cylinder co-axial with and surrounding the aforesaid cylinder and in engagement therewith, said cylinders having co-operating 30 ports, and means for feeding lubricant to engaged portions of the cylinders between said ports and the engine shaft, the portions of the cylinders thus lubricated being relatively formed for diverting the flow 35 of lubricant from the ports.

6. An internal combustion engine including an engine rotated valving cylinder having a port, a second cylinder co-axial with the first and in engagement therewith, and 40 means for feeding lubricant to engaged portions of the cylinders between said port and the engine shaft, portions of the cylinders thus lubricated being relatively formed for diverting the flow of lubricant from the 45 port.

7. An internal combustion engine including an engine rotated valving cylinder which also constitutes the working cylinder of the engine, a piston operating within said cylinder for turning the engine shaft, a second cylinder co-axial with and surrounding the aforesaid cylinder and in engagement therewith, said cylinders having co-operating 50 ports, and means for feeding lubricant to engaged portions of the cylinders between 55

said ports and the engine shaft, portions of the cylinders thus lubricated being relatively formed for diverting the flow of lubricant from the ports.

8. An internal combustion engine including an engine valving cylinder having a port, a second cylinder co-axial with the first and in engagement therewith, and means for feeding lubricant to engaged portions of the cylinders, portions of the cylinders thus lubricated being relatively formed for diverting the flow of lubricant to cause it to be fed in a direction away from the port.

9. In an internal combustion engine, the combination with a ported cylinder casing, of a rotatable valve cylinder, a piston adapted to work in the latter, means for supplying lubricant over a portion of the surface of the valve cylinder, and means for 85 relieving the pressure of the lubricant at a point to prevent feeding of lubricant over a remaining portion of the valve cylinder.

10. In an internal combustion engine, the combination with a ported cylinder casing, of a rotatable valve cylinder, means for supplying lubricant over a portion of the surface of the valve cylinder, and means for relieving the pressure of the lubricant at a 90 point to prevent feeding of lubricant over a remaining portion of the valve cylinder.

11. An internal combustion engine including an engine rotated valving cylinder having a port, a second cylinder co-axial with the first and in engagement therewith, and means for feeding lubricant to engaged portions of the cylinders, portions of the cylinders thus lubricated being relatively formed for diverting the flow of lubricant to cause 100 it to be fed in a direction away from the port.

12. In an internal combustion engine, the combination with a ported cylinder casing, of a rotatable valve cylinder, a piston adapted to work in the latter, means for supplying lubricant under force over a portion of the surface of the valve-cylinder, and means for relieving the pressure of the lubricant at a 105 point to prevent forced feed of the lubricant over the remaining portion of the valve-cylinder.

13. In an internal combustion engine, a casing, a movable cylinder therein, and means for forcibly feeding lubricant over a 110 portion of the surface of the cylinder, the cylinder and casing being relatively formed at a predetermined point to relieve the pressure on the lubricant to prevent forced feed of the latter over the remaining portion of 115 the cylinder therebeyond.

14. In an internal combustion engine, a casing, a movable cylinder therein, and means for forcibly feeding lubricant over a portion of the surface of the cylinder, the 120

cylinder and casing being relatively formed at a predetermined point to permit escape of the lubricant in its travel away from the cylinder to prevent forced feed of the lubricant in that portion of the surface of the cylinder therebeyond.

15. In an internal combustion engine, a casing, a movable cylinder therein, and means for forcibly feeding lubricant over a 10 part of the surface of the cylinder to a predetermined point between the cylinder and casing, said cylinder and casing being relatively formed to enlarge the oil receiving chamber at said point to relieve the pressure 15 on the lubricant and to permit the same to escape away from the remaining portion of the cylinder therebeyond.

16. In an internal combustion engine, means for lubricating coating parts thereof 20 while protecting adjacent parts from the objectionable effects of lubricant, comprising in combination with rotatably associated interfitting members, of means for forcibly feeding lubricant over a portion of the contacting area between said members, and means for preventing forced feed of the lubricant over that area between said members located beyond said last mentioned means, said preventative means including 25 the relative formation of said members to enlarge the lubricant chamber and to permit the escape of the lubricant.

17. In an internal combustion engine, means for lubricating coating parts thereof 30 while protecting adjacent parts from the detrimental effects of lubricant, comprising in combination with rotatably associated interfitting members, means for forcibly feeding lubricant over a portion of the contacting area between said members, and means 35 for preventing forced feed of the lubricant over that area between said members located beyond said last mentioned means, said preventative means including a relative 40 formation of said members to relieve the lubricant of its force at the predetermined point in its travel.

18. In an internal combustion engine, means for lubricating coating parts thereof

of while protecting adjacent parts from the 50 objectionable effects of lubricant, comprising in combination with rotatably associated interfitting members, means for forcibly feeding lubricant over a portion of the contacting area between said members, and 55 means for preventing forced feed of the lubricant over that area between said members located beyond said last mentioned means, said preventative means including an escape for the lubricant at a predetermined 60 point permitting the same to pass away from the area to be protected and overcomes the tendency of the lubricant to feed to a harmful degree outside of its designed course of travel.

19. In an internal combustion engine, the combination with a ported cylinder casing, of a valve cylinder in moving relation to the cylinder casing, means for supplying lubricant over a portion of the surface of 70 the valve cylinder and means for diverting lubricant at a point to prevent feeding of lubricant over a remaining portion of the valve cylinder.

20. In an internal combustion engine, the 75 combination with a ported cylinder casing, of a valve cylinder in moving relation to the cylinder casing, means for supplying lubricant over a portion of the surface of the valve cylinder, and means for diverting the 80 lubricant at a point to prevent the feeding of lubricant into the port.

21. In an internal combustion engine, the combination with a ported cylinder casing of a valve cylinder in moving relation to 85 the cylinder casing, means for supplying lubricant over a portion of the surface of the valve cylinder, there being facility between the cylinder and casing for diverting the lubricant at a point to prevent the feeding 90 of lubricant into the port.

In witness whereof, I hereunto subscribe my name this 12th day of May A. D., 1915.

ROY W. IDE.
